UNITED STATES PATENT OFFICE.

WILLIAM T. CLINGER, OF OIL CITY, PENNSYLVANIA.

SUCKER-ROD ELEVATOR.

1,106,130.

Specification of Letters Patent.

Patented Aug. 4, 1914.

Application filed February 24, 1914. Serial No. 820,703.

To all whom it may concern:

Be it known that I, WILLIAM T. CLINGER, a citizen of the United States, resident of Oil City, county of Venango, and State of

5 Pennsylvania, have invented a new and useful Improvement in Sucker-Rod Elevators, of which the following is a specification, the principle of the invention being herein explained and the best mode in which I have 10 contemplated applying that principle, so as to distinguish it from other inventions.

My invention relates to means for withdrawing sucker-rods from oil wells, such means being usually referred to in the art as 15 sucker-rod elevators.

The object of the device is to provide means of the above described character which will be simple in form, economical of manufacture and efficient in operation.

20 The said invention consists of means hereinafter fully described and particularly set forth in the claims.

The annexed drawing and the following description set forth in detail certain means 25 embodying my invention, the disclosed means, however, constituting but one of various mechanical forms in which the principle of the invention may be applied.

In said annexed drawing:—Figure 1 represents 30 a perspective view of a sucker-rod elevator, showing the upper end of a sucker-rod attached thereto. Fig. 2 represents a view similar to that of Fig. 1, showing the parts in a different position. Fig. 3 represents 35 a partial vertical section of the parts shown in Fig. 1 and showing same in the position in which they are shown in the latter figure. Fig. 4 represents a perspective view showing the parts in still another position.

The illustrated embodiment of my invention 40 comprises a main-member 1 whose upper end is, in the usual manner, provided with a swiveled link 2 to which the elevating rope may be attached. Also as in devices of similar character, the lower end is provided with two arms 3, 3, the lower end of each of which is provided with a bearing 4 for receiving the trunnions 5 of the slotted plate 6. This plate is similar to those heretofore employed excepting that the slot 7 does not intersect the plate angularly as has heretofore been the custom. This said slot 7 is adapted to engage the upper end of the sucker-rod beneath the threaded sleeve 9, as shown in Fig. 1.

Forming an integral part of the main-member 1 and located intermediately of the two arms 3, 3, is a downwardly extending guiding-stem 10 whose lower end lies in a horizontal plane above the end of the sucker-rod, when the latter is in position in the plate and said plate occupies a horizontal position, as shown. Slidable upon said guiding-stem 10 is a sleeve 11 of inverted cup-shape form and having an interior recess 12 adapted to receive the sleeve 9 of the sucker-rod. The upper end of said sleeve is provided with a groove 13 adapted to receive a key or tongue 14 fixedly secured to 70 or integrally formed with the guiding-stem 10, so that said key or tongue may pass through the upper end of the sleeve, as will be readily understood.

In the above described construction, it 75 will be seen that the sleeve 11 may be turned so as to permit the key to pass through the slot 13, then raised into the position shown in Fig. 3, and then turned so as to bring the slot 13 out of register with said key, 80 the sleeve being thus permitted to hang in this lifted or raised position. When the parts are in the above described position, the main member 1 may be turned downwardly as shown in Fig. 4, and in this position the 85 plate 6 may be readily caused to engage the upper end of the sucker-rod as shown. When it is desired to pull the sucker-rods, the upper end of the latter is caused to engage the slot, as shown in Fig. 4, main-member 1, raised into a vertical position as shown in Fig. 1, the sleeve 11 turned so as to bring the slot 13 into register with the key or tongue 14, the sleeve then permitted to drop so as to inclose the sleeve 9 of the 95 sucker-rod, and the sleeve then turned so as to bring the slot 13 out of register with the key or tongue 14. When the parts are in this position, it will be observed that the upper end of the sucker-rod is prevented from 100 disengaging the plate 6, in which position the rods may be pulled, as will be readily understood. It will also be observed that when the parts are in the above described position, the lower end of the guiding-stem 105 10 engages the upper end of the sleeve 11, the length of such stem being made sufficient for such purpose, so that the main-member 1 is maintained in a vertical position without further support, an advantage which will be 110 recognized by those skilled in the art.

When it is desired to disengage the device

from the sucker-rod, the order of manipulating the various parts as above described, is reversed.

By means of the above described construction, I obtain a sucker-rod elevator which is so arranged that when the rods are being pulled, all danger of the elevator becoming disengaged from the rods, with the consequent deleterious results, is eliminated, as 10 will be readily understood by those skilled in the art.

Having fully described my invention, what I claim and desire to secure by Letters Patent is:—

- 15 1. In a sucker-rod elevator, the combination of a main bifurcated member; a member pivotally mounted upon the latter and adapted to detachably engage a sucker-rod; a guiding stem rigidly connected with said main member and projecting between said bifurcations; and a slidable member on said guide-member adapted to engage the end of a sucker-rod while held in said pivotally mounted member.
- 20 2. In a sucker-rod elevator, the combination of a main member; a member pivotally mounted upon the bifurcations of the latter and adapted to detachably engage a sucker-rod; a guiding-stem rigidly connected with said main member; a slidable sleeve mounted upon said guiding-stem and adapted to engage the end of a sucker-rod while held in said pivotally mounted member; and means for locking said sleeve 35 against sliding movement upon said stem.
- 25 3. In a sucker-rod elevator, the combination of a main-member; a slotted plate pivotally mounted upon the latter; a downwardly extending guiding-stem rigidly connected with said main-member and terminating in a plane above said plate when the latter is in a horizontal position; a sleeve mounted and slidable upon said stem and formed with a recess adapted to engage the 40 end of a sucker-rod; and means for locking said sleeve in such engaging position.
- 30 4. In a sucker-rod elevator, the combination of a main-member; a slotted plate pivotally mounted upon the latter; a downwardly extending guiding-stem rigidly connected with said main-member and provided with a tongue, said stem terminating in a plane above said plate when the latter is in a horizontal position; a sleeve mounted and slidable on said stem and provided with a groove adapted to engage said tongue, said sleeve having its lower surface intersected by a recess adapted to engage the end of a sucker-rod.
- 35 5. In a sucker-rod elevator, the combination of a main-member; a slotted plate pivotally mounted upon the latter; a downwardly extending guiding-stem rigidly connected with said main-member and provided with a tongue, said stem terminating in a plane above said plate when the latter is in a horizontal position; a sleeve mounted and slidable on said stem and provided with a groove adapted to engage said tongue, said sleeve having its lower surface intersected by a recess adapted to engage the end of a sucker-rod; said tongue being of a length such that said groove may disengage same when in such engaging position.
- 40 6. In a sucker-rod elevator, the combination of a main-member; a slotted plate pivotally mounted upon the latter; a downwardly extending guiding-stem rigidly connected with said main-member and provided with a tongue, said stem terminating in a plane above said plate when the latter is in a horizontal position; a sleeve mounted and slidable on said stem and provided with a groove adapted to engage said tongue, said sleeve having its lower surface intersected by a recess adapted to engage the end of a sucker-rod; said tongue being of a length such that said groove may disengage same when in such engaging position; and so as to permit said groove to likewise disengage same when in a raised or disengaging position.

extending guiding-stem rigidly connected with said main-member and provided with a tongue, said stem terminating in a plane above said plate when the latter is in a horizontal position; a sleeve mounted and slid able on said stem and provided with a groove adapted to engage said tongue, said sleeve having its lower surface intersected by a recess adapted to engage the end of a sucker-rod.

5. In a sucker-rod elevator, the combination of a main-member; a slotted plate pivotally mounted upon the latter; a downwardly extending guiding-stem rigidly connected with said main-member and provided with a tongue, said stem terminating in a plane above said plate when the latter is in a horizontal position; a sleeve mounted and slid able on said stem and provided with a groove adapted to engage said tongue, said sleeve having its lower surface intersected by a recess adapted to engage the end of a sucker-rod; said tongue being of a length such that said groove may disengage same when in such engaging position.

6. In a sucker-rod elevator, the combination of a main-member; a slotted plate pivotally mounted upon the latter; a downwardly extending guiding-stem rigidly connected with said main-member and provided with a tongue, said stem terminating in a plane above said plate when the latter is in a horizontal position; a sleeve mounted and slid able on said stem and provided with a groove adapted to engage said tongue, said sleeve having its lower surface intersected by a recess adapted to engage the end of a sucker-rod; said tongue being of a length such that said groove may disengage same when in such engaging position; and so as to permit said groove to likewise disengage same when in a raised or disengaging position.

Signed by me this 18th day of February, 1914.

WILLIAM T. CLINGER.
